FIG. 1.

FIG. 2.

FIG. 3.

Inventor
Franklin P. Toof

By *John A. Lancaster* and *A. J. Morris*
Attorneys

UNITED STATES PATENT OFFICE.

FRANKLIN P. TOOF, OF PADUCAH, KENTUCKY.

MOP.

Application filed February 17, 1921. Serial No. 445,683.

To all whom it may concern:

Be it known that I, FRANKLIN P. Toof, a citizen of the United States, residing at Paducah, in the county of McCracken and State of Kentucky, have invented certain new and useful Improvements in Mops, of which the following is a specification.

The present invention relates to mops and more particularly to that class of mops adapted for cleaning and polishing floors or for dry cleaning walls, ceilings, plate rails, etc.

More specifically the invention is an improvement in the mop disclosed in Patent No. 1,281,883 granted to me October 15, 1918. With mops of this character it is desirable that the mop frame be pivotally connected to the handle as by a coupling, an example of which is shown in Patent No. 1,347,563 granted to me July 27, 1920, so that the swab may engage the floor or other surface over which it is moved, with maximum surface contact, the operator pulling and pushing the mop back and forth in the act of cleaning or polishing of the surface. If this connection between the handle and swab frame is stiff, so to speak, the swab is apt to wear unevenly or the strands become bunched at the front or back, according to the position of the frame with respect to the handle where it sticks due to stiffness of the connection. On the other hand, if the connection is loose and the amplitude of oscillation of the frame on the coupling is not limited, the frame with the swab thereon is apt to swing to an undesirable position whenever the mop is lifted from engagement with the floor or other surface, and an attempt is again made to place it into operative relation to the surface. This is due to the force of gravity acting upon the swab and frame, which in practice cannot be so minutely balanced with respect to the pivot as to remain in a horizontal plane, but swings usually so that its forward portion is uppermost. This type of mop is usually shipped, stored, and at times vended with the swab disconnected from the frame. Also in use a person may have two swabs for use with a single frame, one swab being oiled or saturated with polishing material for the polishing of floors and one dry for cleaning walls, etc. These mops are therefore made so that the swab may be readily placed or

simplicity the swab may be placed on the frame with the strands to extend to either one or the other side of the plane of the frame.

The principal object of the present invention is therefore to provide a mop embodying a device which limits the amplitude of oscillation of the frame with respect to the handle, so that the frame cannot swing to a position where placing the swab into operative relation to the surface on which it is to be used would be awkward. A further object of the invention is to provide this device so that it will operate regardless as to which side of the frame the strands of the swab project.

Another object of the invention is to provide a mop having these advantages without materially increasing the cost of manufacture.

Other objects and advantages of the invention will appear in the following detailed description, taken in connection with the accompanying drawing, forming a part of this specification and in which drawing:

Figure 1 is a side elevation of a mop of the character to which my invention may be applied.

Fig. 2 is a detailed view partly in elevation and partly in vertical section of the swab frame, handle portion and coupling.

Fig. 3 is a similar view partly in plan and horizontal section.

In the drawing where similar characters refer to similar parts throughout the views, A designates a swab frame; B a swab; C a handle; D a coupling between the frame A and handle C; and E a device to limit the amplitude of oscillation of the frame with respect to the handle.

The frame A in the example shown, is made of wire including a pivot section 4 and swab receiving sections 5 and 6, the pivot section being connected with the swab receiving sections by rearwardly extending arms 7 in spaced relation, all of which are in substantially the same plane.

The swab B may be of the usual type having strands 8 extending from a sheath 9, which latter may be readily threaded onto or removed from the frame sections 5 and 6, with the strands extending to either one side or the other of the plane of the frame.

Handle C is also of the usual formation, preferably round so as to be readily grasped

in the hands and of a length to be easily manipulated by a person when standing for guiding the swab over the surface acted upon. The end of the handle connected with coupling D may be in telescopic or screw threaded engagement therewith.

As to coupling D it is preferably made from sheet metal having a transverse bearing 10 embracing the pivot section 4 of frame A, and complementary longitudinally extending socket sections 11 to receive the end portion of handle C. These sections 11 are substantially semi-circular in cross section and preferably connected together at their ends remote from bearing 10 as by rivets 12 extending through lateral ears 13 formed integral with the sections 11. In the example shown the central portion 14 of bearing 10 is preferably of U-shaped cross section as shown in Fig. 2 while the end portions 15 are substantially circular in cross section. Thus, a substantial bearing is provided for pivot section 4 of the frame adjacent the arm 7, leaving the central portion of pivot section 4 only partly embraced. The socket sections 11 provide a cavity 16, and serve as abutments as hereinafter noted.

The device E may consist of a lug 17 carried by the pivot section 4 of frame A, preferably midway of its ends, so as to project into the cavity 16, in the example shown, and to engage the inside surfaces of the sections 11 one at a time, which act as abutments to limit the amplitude of oscillation of the frame with respect to the handle C. This lug 17 may be conveniently formed integral with the pivot section 4 by striking the same with a blow directed laterally against the metal by a die, not shown in the drawings, which forms a recess 18 and forces the metal to project laterally of the pivot section as shown in Figures 2 and 3 of the drawing. In the example shown this lug projects laterally from the pivot section in the same plane as the frame A since the handle may be swung to extend from either side of the plane of said frame. It is of a width that it will engage either abutment 11 and limit the amplitude of oscillation of the frame with respect to the handle through an arc of substantially 90° , so that the acute angle between the plane of the frame and longitudinal axis of the handle will not ordinarily exceed 45° no matter from which side of the plane of the frame the handle extends.

Thus, if the mop shown in Fig. 1 is lifted

so its swab does not engage the floor, its rear end portion will not swing downwardly due to the force of gravity, or in other words the mop will not flop backwardly and assume an awkward position making it difficult to again place the swab into operative relation to the floor.

The user in placing a swab is not required to dispose it with the strands extending from any particular side of the plane of the frame, since the frame, coupling, and handle are symmetrical, and the device E will operate for the purpose set forth to limit the amplitude of oscillation of the handle at either side of the plane of the frame.

I claim:

1. In the combination of a frame, including a transversely disposed pivot section, a handle, a coupling pivotally connecting said handle and said frame, said coupling embracing said pivot section of the latter and having confronting abutments at each side of the axis of said pivot section, and a lug carried by the said pivot section of said frame and adapted to engage said abutments one at a time, to limit the amplitude of oscillation of said frame with respect to said handle.

2. In the combination of a wire frame shaped to provide a transverse pivot section having a laterally extending lug integral therewith, a handle, and a coupling pivotally connecting said handle and said frame, said coupling embracing the said pivot section of said frame and provided with abutments positioned to engage, one at a time, said lug to limit the amplitude of oscillation of said frame with respect to said handle.

3. In a device of the class described, the combination of an attaching frame, having the parts thereof lying in the same plane and including a portion provided with a lug struck therefrom, rigid therewith, and extending in the same plane as the frame, and a coupling pivotally connected to the portion of said frame upon which said lug is formed, said coupling having an opening interiorly thereof for receiving the lug upon said frame to provide abutments for engagement with said lug and whereby said coupling may be swung into acute angular relation upon either side of the plane of said frame, said abutments adapted for engaging said lug to limit the relative oscillation of the frame and coupling.

FRANKLIN P. TOOF.
